(57) **CLAIM**

We claim the ornamental design for a feathered friction turkey call, as shown and described.

DESCRIPTION

FIG. 1 is a front perspective view of a feathered friction turkey call showing our new design;

FIG. 2 is a rear perspective view thereof with the plunger shown in an alternate position of use;

FIG. 3 is a rear view of FIG. 2;

FIG. 4 is a front view of FIG. 2;

FIG. 5 is a right side view of FIG. 2;

FIG. 6 is a left side view of FIG. 2;

FIG. 7 is a top view thereof; and,

FIG. 8 is a bottom view thereof.
